US00D959335S

(12) **United States Design Patent** (10) Patent No.: **US D959,335 S**
(45) Date of Patent: ** Aug. 2, 2022

(54) **MOTORCYCLE**

(71) Applicant: **YAMAHA HATSUDOKI KABUSHIKI KAISHA**, Shizuoka-ken (JP)

(72) Inventors: **Luca Julianelli**, Gerno di Lesmo (IT); **Kosei Yamashita**, Shizuoka-ken (JP)

(73) Assignee: **YAMAHA HATSUDOKI KABUSHIKI KAISHA**

(**) Term: **15 Years**

(21) Appl. No.: **29/772,023**

(22) Filed: **Feb. 26, 2021**

(30) **Foreign Application Priority Data**

Aug. 31, 2020 (JP) 2020-018253
